FOREIGN PATENT DOCUMENTS

CN 203506111 U 4/2014

Primary Examiner — Paul D Bohannon(74) *Attorney, Agent, or Firm* — Knobbe, Martens, Olson & Bear, LLP(57) **CLAIM**

The ornamental design for an outdoor chair, as shown and described.

DESCRIPTION

FIG. 1 is a front perspective view of an outdoor chair, according to our new design;

FIG. 2 is a rear perspective view thereof;

FIG. 3 is a front view thereof;

FIG. 4 is a rear view thereof;

FIG. 5 is a left-side view thereof;

FIG. 6 is a right-side view thereof;

FIG. 7 is a top view thereof; and,

FIG. 8 is a bottom view thereof.

Broken lines are used to illustrate portions of the outdoor chair that form no part of the claimed design.

1 Claim, 8 Drawing Sheets(56)
